Primary Examiner — S. Bryan Reinholdt, Jr.*Assistant Examiner* — Kaitlan Walker(74) *Attorney, Agent, or Firm* — NKL Law; Allen Xue(57) **CLAIM**

I claim the ornamental design for a scope reticle, as shown and described.

DESCRIPTION

FIG. 1 is a front view of a scope reticle, showing my new design;

FIG. 2 is a rear view thereof; and

FIG. 3 is a reference view thereof showing the area indicating from where an enlarged view is taken; and,

FIG. 4 is an enlarged view of portion 4 shown in FIG. 3. The dash-dash broken lines in the drawings show portions of the scope reticle which form no part of the claimed design. The dot-dash broken lines are enlargement frames and lead lines that form no part of the claimed design.
